UNITED STATES PATENT OFFICE.

JOHN F. HAMER, OF PUKWANA, SOUTH DAKOTA.

VAPORIZER.

1,385,680.

Specification of Letters Patent. Patented July 26, 1921.

Application filed August 16, 1920. Serial No. 403,987.

To all whom it may concern:

Be it known that I, JOHN F. HAMER, a citizen of the United States, residing at Pukwana, in the county of Brule and State of 5 South Dakota, have invented a new and useful Improvement in Vaporizers, of which the following is a specification.

This invention relates to improvements in vaporizing devices and particularly to improvements for supplying the carburetor or similar devices for combustion engines with a mixture of atomized liquid fuel and air. The invention contemplates the provision of means for permitting the discharge of exhaust gases from the fuel conduit in the event that the engine should back-fire.

It is also an object of the present invention to initiate the vaporization of fuel in the fuel tank by the admission of atmospheric air into the tank.

Another object of the invention is furthermore to provide a connection between an air valve on the gasoline tank and the throttle of the engine, whereby upon operation of the 25 throttle the air valve also is automatically operated.

With these and other objects in view an embodiment of the invention is illustrated in the accompanying drawing and is described 30 in the following specification, the novel features being pointed out in the appending claims.

In the drawings:

Figure 1 is a diagrammatical side elevation and part section of the improved fuel feeding device;

Fig. 2 is a diagrammatical part elevation and part section of a modified embodiment of the device.

The carburetor 1 may be of any suitable construction and may comprise a float chamber 2 and a mixing chamber 3; the latter is connected by means of a conduit 4 with an auxiliary tank 5 containing the fuel. A 45 valve 6 is contained in the conduit 4 for regulating the supply of fuel from the tank 5 or for shutting off this supply. The float chamber communicates through a pipe 7 with a gasoline tank 8 of any suitable construction. This tank has a valve body 12 movable within a nipple 13 which is secured to an opening in the tank. A spring 14 surrounding the stem 15 of the valve body and pressing the washer 16 in the stem 15 upwardly has a tendency to maintain the valve 55 in closing position.

When it is desired to supply a mixture of fuel and air to the carburetor the valve 6 is closed and the valve 12 opens in response to engine suction to admit air into the tank 8. 60 The vapor of gasoline mixed with the incoming air rises and escapes through the conduit 7 which terminates at the float chamber 2. This conduit contains a check valve 17 permitting the flow of the fuel mixture 65 in a predetermined direction and preventing the flow of combustion gases in the opposite direction. This flow of combustion gases might be set up if the engine back fires. The combustion gases then go through 70 the conduit 7 to a relief valve 18 including a valve seat 19 and a ball 19, the ball being normally pressed on its seat by means of a spring 20. The pressure of the combustion gases in back firing will lift the ball from 75 its seat to permit the escape of the gases.

It will be observed that the tank 5 supplies liquid fuel, which may be atomized in the usual way in the carburetor, and when desired this source of liquid fuel may be employed with the supply of carbureted air from the tank 8, by opening slightly the valve 6. This is entirely within the option 80 of the operator, and acts as an economizer, employing the otherwise dissipated gases 85 generated in the tank 8.

In the embodiment illustrated in Fig. 2 the form of the valve in the tank is slightly modified and the valve 28 is normally pressed against its seat 29 by a spring 30 which surrounds the freely movable stem 31 of the valve. This stem is provided at its upper end with an enlargement or head 32. The bell crank lever 33 engages with one arm 90 below the head, while the other arm of the 95 bell crank lever is connected by a rod 34 with a second bell crank lever 35. This second bell crank lever is also associated through its other arm by a link 35^a with the rod 36 which usually extends through the 100 steering post 37 and which carries at its upper end an arm 41 operating on a segment on the steering wheel and providing the hand control of the throttle. A finger 38 at the foot end of the rod is connected 105 by means of the link 39 with a crank arm 40 for the adjustment of the throttle. Check and relief valves 42 and 43, respectively, are provided in this form of the invention and operate similarly to the valves 17 and 18 110 hereinbefore described.

It will be seen, therefore, that upon suit-

able adjustment of the throttle rod 36 for the purpose of regulating the fuel or air supply to the carbureter the valve on the gasoline tank also will be lifted from its seat to permit the inflow of atmospheric air into the tank. This air combined with the vapor of gasoline arising from the fuel within the tank will then form a mixture which can be introduced into the carbureter.

10 I claim:

1. In a vaporizer, the combination of a tank containing liquid fuel, a carbureter, a conduit leading from the tank to the carbureter, a valve for permitting admission of air under atmospheric pressure to the tank in response to engine suction through the carbureter, a throttle for the carbureter, and means operatively connecting the throttle and valve for simultaneous control.

20 2. In a vaporizer, the combination of a tank containing liquid fuel, a carbureter, a conduit leading from the tank to the carbureter, a valve for permitting admission of air under atmospheric pressure to the tank in response to engine suction through the carbureter, a throttle for the carbureter and a link connecting the throttle with the spring actuated valve for permitting simultaneous control of the same.

30 3. In a vaporizer, the combination with a carbureter having a mixing chamber, a throttle for controlling the outlet from said mixing chamber, and manual means for actuating the throttle, of a tank containing liquid fuel, a conduit connected to said tank above the level of liquid fuel therein and leading to the mixing chamber, a valve in said tank above the level of fuel therein, and means connecting said valve and throttle

40 for simultaneously operating the same and for permitting air to enter the tank and pass carbureted to the mixing chamber in response to engine suction.

45 4. In a vaporizer, the combination with a carbureter having a mixing chamber, a throttle for controlling the outlet from said mixing chamber, and manual means for

actuating the throttle, of a tank containing liquid fuel, a conduit connected to said tank above the level of liquid fuel therein and leading to the mixing chamber, a valve in said tank above the level of fuel therein and link and rod mechanism connecting said throttle actuating means and said valve, whereby upon opening of the throttle said valve will open permitting air under atmospheric pressure to pass through the tank in contact with the fuel therein, thence carbureted to the carbureter in response to engine suction.

60

5. The combination with a carbureter having a mixing chamber and a throttle controlling the outlet thereof, of a fuel container, a conduit connected to said container above the level of liquid fuel therein and leading to the carbureter, a check valve in said conduit permitting passage of fuel in one direction only, a relief valve also in the conduit, and a valve in said container above the level of liquid fuel therein for admitting air under atmospheric pressure to said container, in response to engine suction, only when the throttle is open.

70

6. The combination with a carbureter having a mixing chamber and a throttle controlling the outlet thereof, of a fuel container, a conduit connected to said container above the level of liquid fuel therein and leading to the carbureter, a check valve in said conduit permitting passage of fuel in one direction only, a relief valve also in the conduit, and a valve in said container above the level of liquid fuel therein for admitting air under atmospheric pressure to said container, when the throttle is open, and means connecting the throttle and valve for simultaneous operation.
